UNITED STATES PATENT OFFICE.

EVAN P. KILROY, OF JOPLIN, MONTANA.

HYDROCARBON-OIL BURNER.

Application filed January 16, 1922. Serial No. 529,635.

To all whom it may concern:

Be it known that I, EVAN P. KILROY, a citizen of the United States, residing at Joplin, in the county of Liberty and State of 5 Montana, have invented certain new and useful Improvements in Hydrocarbon-Oil Burners; and I do hereby declare the following to be a full, clear, and exact description of the invention, such as will enable those 10 skilled in the art to which it appertains to make and use the same.

The present invention relates to hydrocarbon burners.

An object of the present invention is to 15 provide a burner which is adapted to feed a quantity of air to the central portion of a flame for insuring complete and satisfactory combustion of the body of gas issuing from the burner opening from center to circumference and to thus produce a burner which 20 is not only more efficient, but which is capable of radiating more heat.

It is well known that in prior oil burners at present in use, the center of the flame is 25 usually of a dull blue color while the outer portion of the flame is of a bright red or yellow color, and is far hotter than the inside or blue portion.

It is therefore another object of this invention to do away with this dull blue central portion of the flame and to render the flame of an even glowing white color and of correspondingly increased heat intensity resulting in the more thorough and complete 35 combustion of the gas or vapor and consequently a more efficient burner from the standpoint of fuel consumption and from the standpoint of production of heat energy.

The present invention further aims at the 40 provision of a novel device for feeding air to the central portion of the flame for promoting combustion thereat.

A still further object of the invention is to provide a novel combination of fuel and 45 air feeding pipes for automatically vaporizing or gasifying the liquid fuel and for heating the air prior to delivery to the middle of the burner and also for protecting such vaporizing and air heating pipes from 50 the intensity of the flame at such portions of the pipes which pass through the flame.

The invention further aims at the provision 55 of a burner of this type, which possesses the above enumerated characteristics, and which may be used in the fire box of a stove and which may be supported upon the grate

bars of ordinary construction and arrangement.

With the foregoing and other objects in view, the invention will be more fully described hereinafter, and will be more particularly pointed out in the claims appended hereto.

In the drawings, wherein like symbols refer to like or corresponding parts throughout the several views,

Fig. 1 is a side elevation partly in section, of a burner constructed according to the present invention and shown as resting upon grate bars of conventional form; and,

Fig. 2 is a top plan view thereof.

Referring to the drawing, the burner comprises a base plate 10 which is of any suitable construction and which preferably has a marginal depending flange 11 arranged for 75 spacing the body portion of the plate 10 above a support to permit free access and circulation of air at the under side of the plate. The plate 10 may be of elongated rectangular construction as shown, and is adapted to 80 be fitted in the fire box of a stove or the like and to be supported upon grate bars 12.

The plate 10 is provided with an upstanding pyramidal projection 13 forming an air feeding mouth and the end walls of which 85 are slotted or recessed as at 14 to receive therethrough the horizontal portion 15 of a vaporizing pipe, the portion 15 having a jet or outlet perforation 16 in its upper side and at the central portion of the pyramidal 90 mouth 13. The projection 13 has a relatively large upper open end 17 providing ample air space beneath and about the pipe portion 15 so that air is permitted to freely co-mingle with the gas escaping through the 95 perforation 16.

The vaporizing pipe 15 has one end turned downwardly through a slot 18 formed in one end of the plate 10 and extending from the base of the mouth 13 to the adjacent extremity of the plate, the lower end of the pipe 15 being closed by a cap 19 for maintaining vapor or gas under pressure in the pipe. The other end of the pipe 15 is curved upwardly or returned in spaced relation 105 above the portion 15, as at 20, and such return portion 20 extends beyond the closed end of the pipe 15 and is carried downwardly through such slot 18 in the plate 10. This latter end of the pipe is the inlet end 110 and is externally threaded as at 21 to receive thereon adjusting and supporting nuts

22 which are clamped against opposite sides of the plate 10, the upper nut preferably having an interposed bracket plate 23 beneath the same and which is adapted to project beyond opposite sides of the slot 18. The lower extremity of the threaded portion 21 of the vaporizing pipe carries a reduction coupling 24 to which is connected a relatively small fuel feeding pipe 25 adapted 10 to conduct kerosene or other suitable hydro-carbon to the vaporizing pipe. If desired, the threaded end 21 of the pipe may have metal filings or other suitable thread-like substance 26 therein for breaking up the 15 fuel and for insuring the heating and filtering of the same as it passes into the vaporizing pipe.

The other end portion of the plate 10 carries an air feeding pipe 27. The pipe 27 20 has a substantially vertical or shank portion, the lower extremity of which is threaded, as at 28, and is adjustably secured through a perforation in the plate 10 by clamping nuts 29 which bind against the opposite sides of 25 the plate 10. The air pipe 27 may therefore be secured in various vertically adjusted positions through the plate 10 and may also be swung upon its longitudinal axis into various angular positions with respect thereto. The lower end of the pipe 27 is closed 30 by a threaded cap 30 and the latter carries upon its upper end a yieldable washer or gasket 31 against which is adapted to seat the lower end of a sleeve valve 32 mounted 35 on the threads 28 and adapted to be turned for movement lengthwise upon the pipe 27, toward and from the yieldable seat 31. The pipe 27 has one or more perforations 33 in its side immediately upon the seat or gasket 40 31, and such openings 33 are adapted to be more or less uncovered by raising the sleeve valve 32 upon the threads 28.

The upper end of the pipe 27 is curved or bent laterally to form an over-hanging portion 34, the free extremity of which is curved downwardly with its axis substantially co-axial with the axis of the mouth 13, when the air pipe is adjusted as shown in Figs. 1 and 2. The over-hanging portion 34 45 is threaded at its lower end and supports a combined spreader and air feeder. The spreader and air feeder is composed of a pair of disks 35 and 36 which are secured together by rivets 37 and spaced apart by 50 washers 38 carried upon the rivets 37 and interposed between the disks 35 and 36. The disk 35, shown as the upper disk, has an internally threaded sleeve portion 39 which is threaded on the pipe 34 and the sleeve 39 55 opens through the disk 35 so as to convey air from the pipes 37 and 34 to the space between the disks 35 and 36. The lower disk 36 has a central depending projection 40 of conical configuration providing a deflector 60 adapted to spread the flame or gas which 65

rises from the perforation 16 to not only enlarge the frame for the purpose of insuring complete combustion, but also for protecting the over-hanging portion 34 of the air pipe and the return portion 20 of the vaporizing pipe, which latter is adapted to extend across the top of the combined spreader and air feeder. 70

In operation, fuel is admitted through the pipe 25 to the vaporizing pipe 20, 15. The 75 combustion of the gas issuing from the jet opening 16 heats the over-hanging portion 20 of the vaporizing pipe and vaporizes the hydro-carbon and places the vapor or gas thus formed under considerable pressure in 80 the pipe portion 15. The gas under pressure issues from the opening 16 and rises with considerable force against the spreader which deflects the gas or flame outwardly about the marginal edges of the disks 85 35 and 36. The heat of the flame as well as the suction produced at the middle portion of the flame creates a suction in the pipe 27 with the result that air is drawn in through the openings 33 and is caused to rise in the 90 pipe 27, be heated in the over-hanging portion 34, and finally distributed uniformly from the spreader and deflector to supply air to the middle portion of the flame. The quantity of air delivered to the middle portion of the flame may be regulated by raising and lowering the sleeve valve 32 for more or less covering the openings 33. 95

It is apparent that the base plate 10 may be seated in the fire box of a stove with the 100 flange 11 of the base plate resting upon the grate bars 12. In this position, the ends of the vaporizing and air feeding pipes project downwardly between the grate bars so that the fuel pipe connection 25 may be 105 made in the ash pit and the burner may receive air upwardly through the mouth 13 from the ash pit as well as through the pipe 27 from the ash pit. This permits the 110 desired regulation of the burning of the flame by regulating the usual air checks or registers in the doors of the ash pit and fire box compartments.

It will also be apparent that the air pipe 27 may be adjusted as above explained, and 115 the vaporizing pipe may also be adjusted not only axially upon the nuts 22, but lengthwise in the slot 18, the slot 18 facilitating the assemblage, knocking down and regulating of the parts of the burner. 120

It is obvious that various changes and modifications may be made in the details of construction and design of the above specifically described embodiment of this invention without departing from the spirit 125 thereof, such changes and modifications being restricted only by the scope of the following claims.

What is claimed is:

1. In hydro-carbon burners, a base plate, 130

- a vaporizing pipe carried by the base plate and looped horizontally over the intermediate portion of the same and having a perforation in the lower portion of the loop beneath the upper portion thereof for providing a flame within the loop, an air pipe mounted upon the base plate and having an over-hanging portion projecting over said perforation in the vaporizing pipe, and a spreader on the lower end of said air pipe over said perforation adapted to spread the flame within the upper portion of said loop, substantially as described.
5. A hydro-carbon burner comprising a vaporizing pipe having a lower portion and an upper return portion, said lower portion having a perforation therein through which gas is adapted to escape to provide a flame beneath said upper portion, an air pipe having one end projecting downwardly in line with said perforation, a spreader connected
- 10 to the lower end of the air pipe and arranged over the perforation adapted to spread the flame, said spreader having radial openings therein communicating with said air pipe adapted to supply air to the interior portion of the spread flame, substantially as described.
- 15 3. A hydro-carbon burner comprising a burner tube adapted to provide a flame, an air tube having a depending portion adapted to align with the flame, a spreader on the lower end of the air tube for spreading the flame and having radial openings communicating with the air tube for feeding air to the interior portion of the spread flame, and an adjustable valve mounted on the air tube for controlling the passage of air therethrough to the interior of the flame, substantially as described.

EVAN P. KILROY.
